UNITED STATES PATENT OFFICE.

CHARLES W. MCCOY, OF WINNIPEG, MANITOBA, CANADA, ASSIGNOR OF THREE-EIGHTHS TO WILLIAM J. GIBSON AND TWO-EIGHTHS TO WILLIAM R. RUNDLE, BOTH OF WINNIPEG, CANADA.

COOLER FOR REFRIGERATORS.

1,111,077.

Specification of Letters Patent. Patented Sept. 22, 1914.

Application filed April 26, 1913. Serial No. 763,874.

To all whom it may concern:

Be it known that I, CHARLES W. McCoy, a citizen of the United States, residing at Winnipeg, in the Province of Manitoba, Dominion of Canada, have invented a new and useful Cooler for Refrigerators, of which the following is a specification.

This invention relates to refrigerators and more particularly to the cooling apparatus therefor.

An object of the present invention is to provide a refrigerator with a tank disposed therein for rotation and into which tank may be placed a freezing mixture.

15 A further object is to provide an improved form of rotatable tank whereby the air coming in contact therewith will be cooled and forcibly hurled therefrom to thereby create a forced draft of cooled air within the refrigerator.

20 A further object is to provide an improved form of rotatable tank adapted to contain a freezing mixture therein whereby the said mixture will be agitated to lower the temperature thereof.

25 With the foregoing and other objects in view which will appear as the description preceeds, the invention resides in the combination and arrangement of parts and in the details of construction hereinafter described, and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:

40 Figure 1 is a front view in elevation of my improved refrigerator with the doors of the cooling compartment open to disclose the cooling means disposed therein. Fig. 2 is a plan view of the tank. Fig. 3 is a fragmentary vertical cross sectional view taken through the center of the said tank.

45 Referring to the drawings in which similar reference numerals designate corresponding parts throughout the several views, 1 is a refrigerator provided with the usual ice compartment 2 extending across the top portion thereof and which compartment is provided with the swinging doors 3 illustrated in Fig. 1 of the drawings in an open position. The improved cooling apparatus

herein described is illustrated in the ice compartment 2 but it is to be understood that it may be applied with equal facility to refrigerators, ice boxes, or cold storage rooms, etc., taking the place of the ice which is ordinarily disposed therein.

The cooler into which the freezing mixture and ice is placed comprises the central portion 4 communicating with which and extending therefrom are the four wings 5. 60 Each of the said wings is provided with a hingedly mounted lid or cover 6 with a suitable latch 7 secured thereto whereby the cover may be held in a closed position. The cooler which is in the form of a tank or receptacle is provided with the circular flue 8 extending centrally therethrough and through which flue extends the vertical shaft 9 which is adapted to support the said cooler or receptacle in a rotatable manner. 65 The circular flue 8 which extends through the central portion of the cooler is considerably larger than the shaft 9 so as to provide an air circulating conduit through the central portion of the cooler whereby an increased radiating surface will be provided in the cooler receptacle.

The shaft 9 is disposed within suitable bearings 10 secured to the upper and lower walls of the compartment 2 and rigidly secured to the shaft 9 adjacent the lower extremity thereof is a belt wheel 11 around which passes the driving belt 12, the latter passing over the pulley of a motor 13, whereby the said shaft 9 may be mechanically 70 operated. Rigidly secured to the upper and lower ends of the cooling receptacle 4 are the cross members 14 which are adapted to engage the shaft 9 and to hold the said cooler receptacle rigidly thereto whereby the same 75 will be rotated by the rotating of the shaft. The motor 13 which represents a source of power is adapted to drive the cooler by gearing or a friction belt 12 which actuates the shaft 9 to thereby rotate the cooler, it 80 being pointed out that the belt is illustrated as a driving mechanism as being silent in operation and practically noiseless. By rotating the said cooling receptacle, the wings 5 thereof will come forcibly against the surrounding air and will thereby cool the same and create a forced draft which will circulate throughout the various portions of the refrigerator to effectually cool the same. The air will also circulate through the central 85 90 95 100 105 110

flue 8 and will be cooled through the said passage, it being noted that the air will be cooled and at the same time will remain in a dry and sanitary condition inasmuch as it 5 does not come directly into contact with the ice and freezing mixture which is disposed within the cooling receptacle 5.

The top cover is provided with lids 6 communicating with the various wings of the 10 cooler and through which the ice and freezing mixture is to be introduced. The mixture which is introduced within the said receptacle or compartment of the cooler is adapted to absorb the heat from the walls of 15 the cooler and from the surrounding air with the result that a considerable lowering of temperature will be obtained and that by a rotating of the said cooler, the various ingredients will more readily pass into solution to thereby absorb the heat as described. 20

From the foregoing it will be apparent that the rotating of the cooler performs the functions and produces the effect of increased radiation by bringing the air forcibly 25 into contact with the side walls of the cooler and to create a forced draft throughout the various parts of the refrigerator and also tends to agitate material disposed within the cooler, to aid the same in passing into 30 solution, and to further bring the various materials into more intimate contact to thereby effect a lowering of temperature. By extending the four wings 5 radially from the central portion 4, it allows the various 35 ingredients disposed therein to be thrown forcibly against the outer extremities of the said wings and to thereby produce the greatest cooling effect at these points, and which points are also the ones which being the 40 farthest from the center of the rotating cooler, contact with a relatively greater amount of air than the portions more centrally disposed.

From the foregoing it will be apparent 45 that refrigeration may be obtained with or without the use of ice and that furthermore when used in connection with ice, the most efficient and economical refrigeration will be obtained, it being pointed out that when it 50 is desired to considerably lower the temperature at any time, the motor may be started and the same rotating the cooler will agitate the various ingredients disposed within the said cooler to immediately reduce the temperature, as described.

Mention is also made of the fact that the cooler may be used to cool rooms, public buildings, etc.

Having thus fully described the invention 60 what I claim to be new and original with me is:—

1. In an apparatus of the class described,

the combination of a refrigerant receptacle with outstanding wings communicating therewith, a central flue extending longitudinally through the said receptacle and providing an air passage therethrough, a shaft extending through said flue and adapted to rotatably support the said receptacle, means for rotating the said receptacle to 65 bring the wings thereof forcibly in contact with the surrounding air to create a positive draft and to cool the same. 70

2. A refrigerant receptacle including a main compartment with a central flue extending therethrough and positioned substantially vertical, a plurality of radially extending wings communicating with said main compartment and with the longitudinal axes thereof substantially parallel to 80 the longitudinal axis of the said flue, and means extending through said flue for the supporting of said receptacle. 75

3. In an apparatus of the class described, a main compartment provided with a central flue extending therethrough, a shaft extending through said flue, and means engaging the said shaft and the said compartment for securing the said compartment thereto, radially extending wings communicating 85 with the main compartment and with their longitudinal axes substantially parallel to the said shaft and with the walls of said wings lying in planes parallel to the shaft and the axis of rotation of the said receptacle, and a cover at the upper extremities 90 of the said wings adapted to maintain the same in a sealed condition. 95

4. An apparatus of the class described, comprising a sealed refrigerant receptacle, 100 said receptacle including a plurality of radial wings in open communication therewith, a central open ended longitudinal flue extending through said receptacle, a shaft extending through said flue, means for holding said shaft in a vertical position, means engaging said receptacle and said shaft for supporting the receptacle out of contact with adjacent objects and to permit the circulation of air through the said flue, the adjacent surfaces of the walls of the radial wings forming reentrant angles, the said walls acting to cool the air in contact therewith and to set up a circulation of air downwardly past the said walls and up through the central flue. 105

In testimony that I claim the foregoing as my own, I have hereto affixed my signature in the presence of two witnesses.

CHARLES W. McCOY.
